UNITED STATES PATENT OFFICE

133,395

DESIGN FOR A LIQUID SPRAYER

Glenn W. Tamm, Chicago, Ill., assignor to
Binks Manufacturing Company, Chicago, Ill., a
corporation of Delaware

Application July 4, 1942, Serial No. 107,426

Term of patent 7 years

To all whom it may concern:

Be it known that I, Glenn W. Tamm, a citizen of the United States and residing at Chicago, county of Cook, and State of Illinois, have invented a new, original, and ornamental Design for a Liquid Sprayer, of which the following is a specification, reference being made to the accompanying drawing, forming a part thereof.

Fig. 1 is a view in side elevation of a liquid sprayer showing my new design;

Fig. 2 is a top plan view thereof with the receptacle in Fig. 1 omitted; and

Fig. 3 is a view in rear elevation of Fig. 2.

The dominant features of the design reside in the portions shown in full lines.

I claim:

The ornamental design for a liquid sprayer, as shown and described.

GLENN W. TAMMEN.
